UNITED STATES PATENT OFFICE.

ALBERT E. ROBINSON AND AUGUSTUS M. SOSA, OF CINCINNATI, OHIO, ASSIGNEES TO THE AMERICAN TOOL WORKS COMPANY, OF CINCINNATI, OHIO, A CORPORATION OF OHIO.

DRILLING MACHINE.

Application filed June 27, 1924. Serial No. 722,857.

Our invention relates to drilling machinery, especially to that type known as radial drilling machines.

It is the object of our invention to provide new and improved means whereby the drill-arm is held in adjusted positions; further, to provide new and improved means whereby to manually control the clamping means for the drill-arm; further, to provide a novel clamping means for clamping the drill-arm in radial positions and whereby the clamp is maintained in operated position; further, to provide clamping means for the drill-arm and novel means for operating the same including a power connecting and disconnecting couple and a switch for controlling the operation of the same, and a manual control for said couple and said switch so related as to arrange said couple for connection and to operate said switch in sequence; further, to provide automatic means for disconnecting said couple; further, to provide clamping means for the drill-arm and novel means for operating said clamp including an electric motor and novel means for operatively connecting said electric motor and said operating means and for disconnecting the same; and, further, to provide clamping means for the drill-arm including an eccentric, a crank for operating the eccentric and novel means for operating said crank.

The invention will be further readily understood from the following description and claims, and from the drawings, in which latter:

Fig. 1 is a side elevation of a drilling machine having our invention embodied therein, partly broken away.

Fig. 2 is a plan view of the same, partly broken away.

Fig. 3 is a vertical section of a detail of a portion of the clamp operating mechanism, taken on the line 3—3 of Fig. 2.

Fig. 4 is an end elevation of a drilling machine having our invention applied thereto, partly broken away.

Fig. 5 is a horizontal section of a detail of the same, taken on the line 5—5 of Fig. 4.

Fig. 6 is a detail of the knock-out mechan-

ism, shown partly in section on the line 6—6 of Fig. 9.

Fig. 7 is a horizontal section of the electric switch, taken on the line 7—7 of Fig. 4.

Fig. 8 is a plan view of our improved device, partly in section on the line 8—8 of Fig. 1.

Fig. 9 is an enlarged plan detail of the same.

Fig. 10 is a vertical cross-section of the same, taken on the line 10—10 of Fig. 9, including a vertical section of the knock-out roller and its support.

Fig. 11 is a detail of the same, shown in horizontal section in the plane of the irregular line 11—11 of Fig. 10.

Fig. 12 is a similar view of the same in assumed position.

Fig. 13 is a detail of the same, taken in the plane of the line 13—13 of Fig. 11.

Fig. 14 is a vertical section of the clamping mechanism, taken on the line 14—14 of Fig. 8.

Fig. 15 is a plan view, partly in section, showing the clamping means and the operating means therefor in unclamped position.

Fig. 16 is a similar view, showing the parts in clamping position.

Fig. 17 is a detail in horizontal section, taken in the plane of the line 17—17 of Fig. 14.

Fig. 18 is a vertical section of our improved device, taken on the irregular line 18—18 of Fig. 8, partly broken away.

Fig. 19 is a cross-section, taken on the line 19—19 of Fig. 2, showing the operating handle for our improved device.

Fig. 20 is a detail of the same, taken in section on the line 20—20 of Fig. 19.

Fig. 21 is a plan view of our improved device, showing a modification, partly broken away, and partly in section on the line 21—21 of Fig. 2; and,

Fig. 22 is a vertical section of the same, taken in the plane of the irregular line 22—22 of Fig. 21.

We have exemplified our invention on a drilling machine comprising a base 21, from which a stationary post 22 extends upwardly, about which there is a rotatable column 100

23, having suitable bearings about the post in usual manner, one of which is exemplified at 24. A drill-arm 25 extends laterally from the column and is adjustable to elevation thereon by slide connection between its bearing 26 and the outer periphery of said column, the adjustment being usually effected by means of an adjusting screw 27 having threaded connection with a suitable 10 nut on the arm, relative rotation between the screw and nut effecting raising or lowering of the drill-arm.

The drill-arm carries a suitable drill-head 28 adjustable laterally thereon on guideways 29, extending lengthwise of the drill-arm, the adjustment being exemplified as effected by a suitable rack 34 on the drill-arm, with which a suitable pinion mounted on the drill-head meshes, the pinion being suitably 20 operated, as by a train of gearing operated by handles 35, 36, on the drill-head.

A suitable drill-spindle 37 is journaled on the drill-head and is arranged to have a suitable drill 38 secured thereto, suitable 25 means being provided for axially feeding the drill-spindle.

In the present exemplification, the column is rotatable on the base for the purpose of adjustment of the drill-arm into suitable 30 radial positions with relation to the base in well-known manner.

The drill-arm is arranged to be clamped in suitable adjusted positions, effected in the present instance by clamping the column to the base, the column has a split-bearing 41 about a lower journal-part 42 of the post. The split-bearing is arranged to be clamped about the post by means of an eccentric 43 on a shaft 44 journaled in bearings 45, 46, 35 located in lugs on said split-bearing, at one side of the split thereof. A link 47 has a bearing 48 about said eccentric and extends through an aperture 49 in a cheek 50 formed as a lug at the other side of said split, and adjustable with relation thereto by means of a nut 51 threaded over the threaded end 52 of said link, a washer 53 being shown between said cheek and said nut. (See Figs. 14 and 17.)

The eccentric is arranged to be rotated, shown accomplished in the present exemplification by an arm 55 secured to said shaft, and means for swinging said arm. The connection between said arm and said shaft is preferably adjustable, as by providing a cone-clutch connection 56 between them, with a nut 57 received over the threaded end 58 of said shaft for clamping said arm to said shaft. (See Fig. 14.)

The eccentric is operable for drawing said split-bearing about the post and clamping it to the base, the locking relation being preferably such that a right line, exemplified at C, drawn through the high point 62 of the eccentric and the axis of rotation 63 of

the shaft, will be parallel with the link 47 or the line of clamping force exerted between the cheeks at the respective sides of the split-bearing, whereby said split-bearing is maintained or locked in clamped relation. (See Figs. 16 and 17.) In such relation an exterior force is required to disturb the clamping relation of the eccentric.

A movement of the eccentric so that its high point is moved away from said right line will cause an unclamping movement in the clamp-bearing, due to the natural resiliency in the metal of said bearing, for releasing its clamping hold upon the post. The extent of such movement is optional, the unclamping position of the eccentric being indicated in dotted lines in Fig. 15. Such movement of the eccentric is accomplished by a movement of the arm 55 into the position shown in Fig. 15. The position of the high point of the eccentric with relation to the axis of rotation of the shaft 44 is then as shown in Fig. 15.

The rotation of the eccentric is in the present instance accomplished by a crank comprising a crank-pin 67 and a crank-arm 68 having an axis of rotation 69, and exemplified as rotated by a gear 70, rotatable about a stud-shaft 71 fixed in a bearing 72 of a gear-box 73 on a bracket 74 extending from the column. The arm is exemplified as fixed to a hub 75 extending from said gear, being, for instance, keyed thereto by a key 76, and held to said hub by a flange 77 on said stud-shaft. (See Fig. 18.)

A link 78 is articulated about the crank-pin at one of its ends, and is at its other end articulated with the arm 55 by a pin 79.

This gear is shown in Figs. 1 to 20 inclusive as a worm-wheel and as engaged by a worm 81 fixed to a shaft 82, journaled in bearings 83, 84, of said gear-box. (See Figs. 5 and 18.) The shaft 82 is exemplified as rotated by the armature-shaft 85 of the electric motor 86, mounted on the bracket 74.

A power connecting and disconnecting couple, exemplified as a clutch 91 is located between the rotatable shaft of the electric motor and the shaft 82, and means are provided for engaging and disengaging said clutch. The clutch is exemplified as comprising a collar 92 fixed to the shaft 82, and a collar 93 having spline-key and groove connection 94 with the shaft 85, the collar 93 being movable lengthwise on said shaft. (See Fig. 5.) Said clutch is exemplified as a tooth-clutch, the teeth of which are on the proximate ends of said collars, said collars representing the members of a power engaging and disengaging couple, which couple may, however, be of other form and be any suitable power engaging or disengaging couple for connecting the power of a motor with the crank.

A switch 101 is located in a switch-box 102 fixed to a pad 103 on the column, and is exemplified as comprising a rockable member 104, on which there are electric contacts 105, 106, electrically connected with each other, arranged to make contact with the electric contacts 107, 108, forming the terminals of a suitable electric motor circuit between a suitable source of electric energy and the motor for operating the electric motor. (See Figs. 4 and 7.)

Means are provided for operating the power connecting and disconnecting couple or clutch and the switch. These means are shown as including manual means for operating the couple and the switch in sequence in the order named, in order that engagement in the clutch shall take place prior to a power application in the motor sufficient to speed up the motor, which would make clutch engagement difficult, or the clutch is placed in relation for readily engaging upon initial rotation of the motor, as will be hereinafter more fully explained.

The manual means for operating the clutch and switch are exemplified as a pair of links 111, 112, the link 111 being in the form of a rod having operative connection with the clutch, and the link 112 having operative connection with the switch. (See Figs. 2, 4 and 8.) These links are respectively articulated by articulations 113, 114, with arms 116, 117, fixed to an upright shaft 118 extending lengthwise of the column and journaled in bearings 119, 120, on the column. The shaft 118 has spline-key and groove connection 121 with a bevel-gear 122 moving with the drill-arm, and the hub of which is journaled in a bearing 123, on a bracket 124 fixed to the bearings 26 of the drill-arm. A bevel-gear 125 meshes with the bevel-gear 122, and is fixed to a shaft 126 journaled in bearings 127 on the drill-arm.

A spring 131 surrounds said shaft, one end of the spring being received in a hole 132 in one of the bearings 127, the other end of the spring being received in a hole 133 in a collar 134, adjustably fixed to said shaft by a set-bolt 135, for adjusting the tension of the spring. The spring normally retracts the links.

A bevel-gear 138 is fixed to the shaft 126, and meshes with a bevel-gear 139 fixed to a shaft 140, journaled in bearings 141 and extending through the drill-arm. This shaft has a bevel-gear 142, fixed thereto, which meshes with the bevel-gear 143 fixed to a shaft 144, journaled in bearings 145, 146, on the drill-arm, and extending lengthwise of the drill-arm.

The shaft 144 is arranged to be rocked for operating the links. (See Figs. 1, 2, 3, 19 and 20.) It is shown provided with a handle 151 which has spline-key and groove connection 152 with the shaft, and is arranged

to move laterally with the drill-head. The hub 153 of the handle is shown provided with an annular groove 154, in which a bolt 155 threaded into a lug 156 on the drill-head is received, for holding the handle and the drill-head in lateral arrangement. The swinging movements of the handle may be limited by striking the lug 156 and a lug 157 on the drill-head.

A rock-shaft 165 is journaled in a bearing 166 in the bracket 74, and has an arm 167 fixed thereto. A block 168 is swiveled to said arm, as on a stub 169 in a bearing 170 of said arm, held to said bearing by a collar 171 and set-screw 172. (See Figs. 10 and 18.)

The block has a trigger 175 pivoted thereto on a pin 176, the trigger having a latch 177 and a heel 178. (See Figs. 11, 12 and 13.) The rod has a latch-piece 181 fixed thereto. The latch and latch-piece having abrupt engaging faces 182, 183, for causing movement of the latch with the latch-piece, during movement of said rod in one axial direction, the said latch and latch-piece being provided with coacting inclined faces 184, 185, for enabling the latch-piece to be received under the latch when said rod is moved in the opposite axial direction. A stop 186 on the latch coacts with the block 168 to maintain the latch in engageable relation with the latch-piece.

The latch is resiliently held for such engageable relation by means of a plug 188, in a bore 189 of the heel 178 of the trigger, the plug being spring-pressed toward the rod by a spring 190 in said bore, and held therein by a threaded plug 191. The rod is provided with a seat 193, shown as a flattened portion of said rod, in which the plug is arranged to normally seat, the coacting end of the plug being preferably rounded, as at 194, so that the rod may be moved axially under said plug by application of sufficient force from the handle. (See Figs. 10, 11 and 12.)

A trip is provided for automatically disengaging the latch during movement of the rod in clutch-engaging direction, so as to permit a further movement of the links in order to operate the switch. Thus a stop 201 is provided, shown as a set-screw adjustable in a threaded hole in a shank 202 extending from and fixed to the bracket 74, and held in adjusted positions by means of a jam-nut 203. This stop is arranged to be engaged by the heel 178 of the trigger, whereby the latch is swung on its pivot for releasing the latch-piece, enabling continuing movement in the same direction of said rod.

Arms 206, 207, are also fixed to said rock-shaft 165 and are provided with pins 208 on which rollers 209 are located, the rollers being received in an annular groove 210 of

the movable member of the clutch for actuating the same. (See Figs. 9 and 10.)

The arm 206 also has a plate 211 fixed thereto, with which a resiliently acting plunger 212 is arranged to coact, for urging the arms in opposite directions, for maintaining the clutch in engaged relation or disengaged relation, according to the directions of movement of said movable clutch-member, and preferably for completing respectively the clutch engaging and clutch releasing movements of said arm. (See Figs. 9 and 10.) For this purpose the plate is provided with notches 215, 216, with the walls of which the plunger is arranged to coact. The coacting faces of the notches and of the plunger are inclined for causing the plunger to automatically move into said notches respectively after the apex 217 between the notches passes the apex 218 of the plunger. The plunger operates in a bore 220 of a barrel 221, supported on the gear-box, and is provided with a stem 222 reciprocating in a hole in a plug 223 in the threaded end of said bore, a spring 224 surrounding said stem between said plug and said plunger for normally urging the plunger toward said plate.

The arm 206 is also provided with a contact part, shown as a roller 226, journaled on a shoulder screw 227, threaded into said arm. (See Figs. 8, 9 and 10.)

Means are provided for automatically disengaging the clutch or power connecting and disconnecting couple, exemplified as knock-out arms, 231, 232, on a knock-out plate 233, rockable about a journal portion 234 of the gear 70, and held to said journal portion by the hub of the crank-arm 68. (See Figs. 8 and 18.)

Resilient yield is permitted to the knock-out arms upon contact with the clutch-arm to avoid shock and jar between the parts, this resilient yield being effected by a spring 237. (See Figs. 8 and 21.) The respective ends of the spring are received about a pin 238 on said knock-out plate and a pin 239 on the gear 70, the said gear being further provided with limiting pins 240, 241.

The knock-out plate is arranged to impinge against the pin 240 for defining its normal position, and the pin 241 limits the yielding movement of the plate, and acts as a stop therefor to definitely control the clutch release.

In operation, when it is desired to clamp or unclamp the radial drill-arm, the operator, whose position is in front of the drill-head, manually operates the handle 151 for causing movement of the links 111, 112, in the direction of the arrow *a*. (See Figs. 4, 8, 11 and 12.) This operation simultaneously moves both links, the first effect of which is, in the present exemplification, for the latch piece 181 to carry the latch 177

with it in its movement, swinging the lever or arm 167 and rocking the shaft 165 for moving the movable member of the clutch toward its mating member so as to cause substantially clutching relation. This same movement moves the arm 206 and the automatic locating plate 211 for causing the apex 217 thereof to pass the apex 218 of the plunger, whereby the spring-pressed plunger causes further movement in the same direction of said arm and said clutch-member. (See Figs. 9 and 21.)

The clutch is exemplified as rotating in the direction of the arrow *b* in Fig. 5. The clutch-teeth preferably have coacting abrupt faces 243 at one of their respective sides and inclined faces 244 at the other of their respective sides, whereby the teeth of the movable clutch-collar are arranged to slide into the tooth-spaces between the teeth of its mating clutch-collar when contact has once been made between the ends of said clutch-teeth.

This sliding movement may be effected by the interaction of the spring-pressed plunger 212 and its coacting plate 211.

There is spaced relation between the electric contacts on the rockable member of the electric switch, as exemplified at 246, (Fig. 7), and its coacting contacts, this spaced relation being provided for the purpose of enabling the power connecting and disconnecting couple, exemplified as the clutch, to be placed in coactive relation for engagement prior to substantial electrically connected relation to the electric switch, in order that such coactive relation for engagement in the clutch may be effected prior to substantial power application by the motor for performing the clamping function, although not necessarily prior to initial rotative impulse is imparted to the motor, whereby shock to the parts and shock and wear between the clutch-teeth is avoided.

When such clutch engagement has been effected and effective power is being applied by the motor, the shaft 82 is rotated for rotating the worm and the worm-wheel and rotating the crank-arm.

A continued movement of the operating handle in the same direction causes a continuation of movement in the same direction of the links. Such continued movement of the rod 111 causes the heel 178 to strike the stop 201 for disengaging the latch 177 from the latch-piece 181, (Figs. 11, 12 and 13), whereby the axial movement of said rod may be continued, for causing continuation of actuation of the electric switch beyond the spaced relation therein for full contact in said switch, in order to supply full current to the electric motor for operation of the same.

The crank-arm is by such power application rotated, exemplified as throughout a

half revolution, whereupon the clutch is disengaged, instanced as accomplished by the knock-out arms engaging the arm 206, the spring 237 avoiding shock to the parts, and 5 the pin 241, limiting the yielding movement of the knock-out arm so as to cause definite relation of clutch disengagement to angle of crank-arm rotation. Such movement carries the apex 217 of the knock-out plate 10 across the apex 218 of the plunger, the spring-pressed plunger completing disengagement of the clutch. (See Figs. 9 and 21.)

As soon as clutch disengagement takes 15 place, rotation of the crank-arm ceases, regardless of continuation of power in the electric motor, and regardless of switch relation. Switch release is effected by release of the operator's handle by the operator, 20 causing the spring 131 to return said handle to normal position, whereby said links are also returned to normal positions. During reverse movement of the link or rod 111, the inclined faces of the latch and its latch- 25 piece coact for raising the latch and permitting the latch-piece to be received behind the latch, thereby resetting said parts for operation for the next clamping or unclamping movement for the operating clamp.

30 The release movement of the clutch is automatically effected in order to provide definite relation between the operating means and the clamp at the clamping and unclamping moments of the clamp.

35 The clamping relation of the clamp is preferably such that a right line drawn through the axis of rotation of the eccentric and the high point of the eccentric is parallel with the line of clamping power between the cheeks at the respective sides of 40 the split-bearing, being exemplified as parallel with the link 47, as exemplified by the dot and dash line *c*. (See Figs. 16 and 17.)

45 This relation insures a maintenance of clamping action of the clamp for maintaining the radial drill-arm in adjusted radial position.

The means for operating the clamp are 50 also preferably such that a right line, exemplified by the dot and dash line *d*, (in Figs. 15 and 16) will intersect the axis of rotation of the crank-arm and the axis of the crank, and be substantially parallel with the link 78, preferably also bisecting the 55 axis of articulation between said link and the arm 55. The axis of said crank is preferably at one side of the axis of rotation of the crank-arm and bisects said right line when the eccentric is in clamping relation, 60 and bisects said right line at the other side of said axis of rotation when said eccentric is in unclamping relation.

The crank is preferably in dead-center position with relation to the clamp-arm when 65 the clamp is in clamping position, and is

shown in dead-center position when the clamp is in clamping relation and in unclamping relation.

In the present exemplification, the clamping action and the unclamping action are 70 alternately effected by successive manual actuations of the handle 151, and by successive operations of the means described for actuating the crank-pin 67. At a given half revolution of the crank-arm 68, the clamp is 75 moved from an unclamped relation, such as shown in Fig. 15, to a clamped relation, such as shown in Fig. 16, and at the next half revolution of the crank-arm 68 in the same direction, the clamp is moved from a 80 clamped relation, such as shown in Fig. 16, to an unclamped relation, such as shown in Fig. 15. The operating links 111, 112, are, for initiating each of said movements, moved in the same direction, as exemplified 85 by the direction of the arrows *a* in Figs. 4 and 8. The arm 55 reciprocates between the positions shown in Figs. 15 and 16.

I have in Figs. 1 to 20 inclusive exemplified a worm and worm-wheel as rotating the 90 crank-arm. If desired, this gear connection may take the form illustrated in Figs. 21 and 22, in which similar parts are represented by similar reference numerals, but the gear connection is shown as a train of bevel 95 and spur gears.

For example, the clutch-collar 92 is fixed to a shaft 251, journaled in a bearing 252 on the gear-box 73. This shaft has a bevel-pinion 253 fixed thereto, which meshes with a bevel-pinion 254, fixed to a shaft 255, journaled in a bearing 256 on said bracket. This shaft also carries a spur-pinion 257 fast thereon, which meshes with a spur-gear 258 rotatable about the stud-shaft 71, the 100 crank-arm being secured to the hub 259 of said spur-gear 258 by spline-key and groove connection 260.

If desired, the gear-box 73 may comprise 105 a lubricant or oil casing 262, in which the worm and worm-wheel and the bevel and spur-gearing are arranged to rotate in such manner as to have continuous supply of lubricant thereto and to their journals.

Having thus fully described our invention, what we claim as new, and desire to secure by Letters Patent, is:

1. In a drilling machine, the combination 110 of a base, a tool-arm adjustable to radial positions thereabove, a clamp for clamping said tool-arm in adjusted position, means for operating said clamp comprising an electric motor, a power connecting and disconnecting couple operatively disposed between said electric motor and said clamp, and a power controlling switch for controlling actuation of said electric motor, said couple including a movable member, a control member, and mechanical connections between said control-member and said mov- 115 120 125 130

- able member and between said control-member and said switch so constructed and arranged as to arrange said couple for connection and to operate said switch for power 5 actuation.
2. In a drilling machine, the combination of a base, a tool-arm adjustable to radial positions thereabove, a clamp for clamping said tool-arm in adjusted position, means for operating said clamp comprising an electric motor, a power connecting and disconnecting couple operatively disposed between said electric motor and said clamp, and a power controlling switch for controlling actuation of said electric motor and a control-member for arranging said couple for connection and for operating said switch for substantially full power-actuation in the sequence named. 10
3. In a drilling machine, the combination of a base, a tool-arm adjustable to radial positions thereabove, a clamp for clamping said tool-arm in adjusted position, means for operating said clamp comprising an electric motor, a power connecting and disconnecting couple operatively disposed between said electric motor and said clamp and a power controlling switch for controlling actuation of said electric motor a control-member for preliminarily arranging said couple for connection and for operating said switch for substantially full power-actuation in the sequence named, and means for automatically completing connection in 15 said couple. 20
4. In a drilling machine, the combination of a base, a tool-arm adjustable to radial positions thereabove, a clamp for clamping said tool-arm in adjusted position, means for operating said clamp comprising an electric motor, a power connecting and disconnecting couple operatively disposed between said electric motor and said clamp, and a power controlling switch for controlling actuation of said electric motor, a control-member for arranging said couple for connection and for operating said switch for substantially full power actuation in the sequence named, and means for automatically disconnecting said couple. 25
5. In a drilling machine, the combination of a base, a tool-arm adjustable to radial positions thereabove, a clamp for clamping said tool-arm in adjusted position, means for operating said clamp comprising an electric motor, a mechanical power connecting and disconnecting couple comprising a movable member and operatively disposed between said electric motor and said clamp, and an electric switch for controlling the operation of said motor, and a control-member having operative connection with said movable member and with said switch for arranging said couple for connection and for operating said switch for substantially 30
- full motor actuation by movement in one direction of said control-member.
6. In a drilling machine, the combination of a base, a tool-arm adjustable to radial positions thereabove, a clamp for clamping said tool-arm in adjusted position, means for operating said clamp comprising an electric motor, a mechanical power connecting and disconnecting couple between said electric motor and said clamp, an electric switch for controlling the operation of said motor, a control-member for arranging said couple for connection and for operating said switch for motor actuation in the sequence named, means for automatically completing connection in said couple, and means for automatically disconnecting said couple. 35
7. In a drilling machine, the combination of a base, a column rotatable on said base, a drill-arm on said column, a clamp between said column and said base, means for operating said clamp including a clutch and an electric switch, and control means which include mechanical connections with said clutch and said switch, said connection with said switch including a spaced connection for retarding electric transmission by said switch. 40
8. In a drilling machine, the combination of a base, a column rotatable on said base, a drill-arm on said column, a clamp between said column and said base, means for operating said clamp including a clutch and an electric switch, control means which include mechanical connections with said clutch and said switch, said connection with said switch including a spaced connection for retarding electric transmission by said switch, and an automatic knock-out for said clutch. 45
9. In a drilling machine, the combination of a base, a column rotatable on said base, a drill-arm on said column, a clamp between said column and said base, means for operating said clamp including a clutch and an electric switch, control means which include mechanical connections with said clutch and said switch, said connection with said switch including a spaced connection for retarding electric transmission by said switch, automatic clutch-engaging means, and an automatic knock-out for said clutch. 50
10. In a drilling machine, the combination of a base, a tool-arm adjustable to radial positions thereabove, a clamp for clamping said tool-arm in adjusted positions, said clamp including an eccentric, and means for rotating said eccentric comprising a crank having operative connection with said eccentric and arranged to rotate said eccentric in opposite directions respectively for clamping and unclamping said clamp by rotations in the same direction of said crank. 55
11. In a drilling machine, the combination of a base, a tool-arm adjustable to 60

radial positions thereabove, a clamp for clamping said tool-arm in adjusted positions, said clamp including an eccentric, means for rotating said eccentric comprising a crank having operative connection with said eccentric and arranged to rotate said eccentric in opposite directions by rotations in the same direction of said crank, and means causing cessation of rotation of said crank at each half-revolution thereof.

12. In a drilling machine, the combination of a base, a drill-arm adjustable to radial positions above said base, a clamp for clamping said drill-arm in adjusted positions including an eccentric, means for rotating said eccentric comprising a crank, and means for interrupting the rotations of said crank alternately at positions in which the axis of said crank is at opposite sides 20 of its axis of rotation and at substantially dead-center positions with relation to the line of clamping force.

13. In a drilling machine, the combination of a base, a drill-arm adjustable to radial positions thereabove, a clamp for clamping said drill-arm in adjusted positions, means for operating said clamp including a crank, a mechanical power connecting and disconnecting couple, a knock-out couple including a knock-out member rotatable with said crank and a member having operative connection with a member of said first-named couple for disconnecting said first-named couple, and cushioning means for said knock-out couple for cushioning the shock of contact between said rotatable knock-out member and its companion member of said second-named couple.

14. In a drilling machine, the combination of a base, a drill-arm adjustable to radial positions thereabove, a clamp for clamping said drill-arm in adjusted positions, means for operating said clamp including a crank, a mechanical power connecting and disconnecting couple, a knock-out couple including a knock-out member rotatable with said crank and a member having operative connection with a member of said first-named couple for disconnecting said first-named couple, cushioning means for said knock-out couple for cushioning the shock of contact between said rotatable knock-out member and its companion member of said second-named couple, and a stop for said cushioning means.

15. In a drilling machine, the combination of a base, a drill-arm adjustable to radial positions above said base, a clamp for clamping said drill-arm in adjusted positions including an eccentric, means for rotating said eccentric comprising a crank, and means for rotating said crank and for interrupting the rotation of said crank at substantially dead-center position with relation to the line of clamping force thereon.

during clamping position of said eccentric, said means for rotating said crank including a mechanical power connecting and disconnecting couple, and an automatic knock-out therefor.

16. In a drilling machine, the combination of a base, a drill-arm adjustable to radial positions thereabove, a clamp for clamping said drill-arm in adjusted position, means for operating said clamp comprising a crank, knock-out means rotating therewith, a mechanical power connecting and disconnecting couple, a lever for operating the same, said knock-out means operating said lever to disconnect said couple, 80 and a manual control means for operating said lever.

17. In a drilling machine, the combination of a base, a drill-arm adjustable to radial positions thereabove, a clamp for clamping said drill-arm in adjusted position, means for operating said clamp comprising a crank, knock-out means rotating therewith, a mechanical power connecting and disconnecting couple, a lever for operating the same, means for resiliently holding said lever for connected relation of said couple, said knock-out means operating said lever to disconnect said couple, and a manual control means for operating said lever.

18. In a drilling machine, the combination of a base, a drill-arm adjustable to radial positions thereabove, a clamp for clamping said drill-arm in adjusted position, means for operating said clamp comprising a rotatable member having operative connection with said clamp to clamp and unclamp the same, an electric motor, a power train between said electric motor and said rotatable member comprising speed reducing gearing and a mechanical power connecting and disconnecting couple, and an automatic knock-out for said couple comprising a member having rotative connection with said rotatable member and a member operated thereby having connection with a member of said couple for automatically disconnecting said couple.

19. In a drilling machine, the combination of a base, a rotatable column thereon, a drill-arm on said column, a drill-head adjustable laterally on said drill-arm, a clamp for clamping said column to said base whereby said arm is clamped in radial position, an electric motor for operating said clamp, a switch controlling the same, a mechanical power connecting and disconnecting couple between said electric motor and said clamp, control means below said arm for connecting said couple and operating said switch, and a manually operated member for said control-means having operative connection with said drill-head for moving laterally therewith.

20. In a drilling machine, the combina-

- tion of a base, a drill-arm adjustable to radial positions thereabove, a clamp for clamping said drill-arm in adjusted position, operating means for said clamp, an electric motor, a mechanical power connecting and disconnecting couple between said electric motor and said operating means, a lever for operating the same, resilient means for maintaining the same in operated position, knock-out means having operative connection with said operating means and acting on said lever to disconnect said couple, and manual control means for connecting said couple.
- 15 21. In a drilling machine, the combination of a base, a drill-arm adjustable to radial positions thereabove, a clamp for clamping said drill-arm in adjusted position, operating means for said clamp, an electric motor, a switch therefor, a mechanical power connecting and disconnecting couple, between said electric motor and said operating means, a lever for operating the same, resilient means for maintaining the same in operated position, knock-out means having operative connection with said operating means and acting on said lever to disconnect said couple, and manual control means for connecting said couple and operating said switch.
- 20 22. In a drilling machine, the combination of a base, a rotatable column thereon, a drill-arm on said column, a drill-head adjustable laterally on said drill-arm, a clamp for clamping said column to said base whereby said arm is clamped in radial position, an electric motor for operating said clamp, a switch controlling the same, a mechanical power connecting and disconnecting couple between said electric motor and said clamp, a pair of links having connections respectively with said couple and said switch, a manual control means for combinedly operating said links, said connection with said couple comprising a latch, and a trip therefor for permitting idle movement of said link connecting with said couple during continuing operating movement of said link connecting with said switch.
- 25 23. In a drilling machine, the combination of a base, a rotatable column thereon, a drill-arm on said column, a drill-head adjustable laterally on said drill-arm, a clamp for clamping said column to said base whereby said arm is clamped in radial position, an electric motor for operating said clamp, a switch controlling the same, a mechanical power connecting and disconnecting couple between said electric motor
- 30 and said clamp, a pair of links having connections respectively with said couple and said switch, a manual control means for combinedly operating said links, said connection with said couple comprising a latch, and a trip therefor for permitting idle movement of said link connecting with said switch, said manual control means having operative connection with said drill-head for moving laterally therewith.
- 35 24. In a drilling machine, the combination of a base, a rotatable column thereon, a drill-arm on said column, a drill-head adjustable laterally on said drill-arm, a clamp for clamping said column to said base whereby said arm is clamped in radial position, an electric motor for operating said clamp, a switch controlling the same, a mechanical power connecting and disconnecting couple between said electric motor and said clamp, a pair of links having connections respectively with said couple and said switch, a manual control means for combinedly operating said links, said connection with said couple comprising a latch, a trip therefor for permitting idle movement of said link connecting with said couple during continuing operating movement of said link connecting with said switch, and automatic knock-out means for said couple.
- 40 25. In a drilling machine, the combination of a base, a rotatable column thereon, a drill-arm on said column, a drill-head adjustable laterally on said drill-arm, a clamp for clamping said column to said base whereby said arm is clamped in radial position, an electric motor for operating said clamp, a switch controlling the same, a mechanical power connecting and disconnecting couple comprising a movable member between said electric motor and said clamp, an arm for operating said movable member, means for resiliently holding said arm in operated position, a link having connection with said arm, a link having connection with said switch, a manual means for combinedly operating said links, said connection with said arm including a latch, a trip therefor for permitting idle movement of said first-named link during continuing operating movement of said second-named link, and automatic knock-out means for said couple.
- 45 In testimony whereof, we have hereunto signed our names.
- 50 ALBERT E. ROBINSON.
AUGUSTUS M. SOSA.
